TEXTILE FLEXING AND ABRASION TESTER

Robert C. Cross, Riverside, and Walter Krauss,
Oak Park, Ill., assignors to Sears, Roebuck and
Co., Chicago, Ill., a corporation of New York

Application October 21, 1944, Serial No. 559,688

4 Claims. (Cl. 73—7)

1

The present invention relates to laboratory fabric testing devices and is concerned particularly with apparatus of this class designed to administer wrinkle and abrasion wearing conditions upon a subjective strip of fabric.

Woven fabrics of cotton, rayon, etc., may be constructed under various conditions of weight and composition to produce variable characteristics of resistance to wrinkling, wear, etc. For purposes of determining under laboratory conditions the individual characteristics of various fabrics, it is proposed to simulate mechanically conditions for inflicting flexure, abrasion and other fabric deteriorating influences in order to determine the resistance qualities thereof within a comparatively brief time interval and in order to make periodic observations under laboratory conditions economically. Towards this end, there is proposed herewith a novel design in textile testing apparatus having incorporated adjustments relative to strain, tension and pressure so that there may be obtained various testing effects to be operated under continuous fatigue conditions and in which the test fabric is held so as to be exposed for observation while wear and other test operations are performed.

A principal object of this invention is to provide a continuous power driven mechanism for subjecting a sample strip of textile material to the above prescribed conditions of wear which will admit of adjustability and variation in its wear administering effects and which may be operated over extensive periods constantly and efficiently.

In the proposed embodiment, the invention contemplates briefly a fabric supporting structure in which a pair of rollers are supported upon a reciprocating rack in a manner which permits of the varying disposition of the rollers between which the material under test is threaded. A power driven assembly operates a crank arm which, through a connecting rod, drives the rollers to and fro under the guidance of a pair of supporting rods. The entire assembly is mounted upon a rectangular base and the supporting rods extend upwardly and are at their extremities steadied by guy or stay wires anchored to the supporting base.

For a more comprehensive understanding of the present invention, reference will now be had to the accompanying drawings and to the following detailed specification, in which like reference characters designate corresponding parts throughout, and in which:

Fig. 1 is a front elevation of a fabric fatigue

2

testing apparatus having incorporated therein predominant features of the present invention;

Fig. 2 is a side elevation of the apparatus featured in Fig. 1;

Fig. 3 is an enlarged plan sectional view of a journal bracket and guide bar assembly, as indicated by the line 2—3 of Fig. 1;

Fig. 4 is an enlarged side sectional view of the mechanical details featured in Fig. 3 and is taken approximately on line 4—4 of Figs. 1 or 3; and

Fig. 5 is a detailed sectional view taken approximately on line 5—5 of Fig. 1, but with the friction rollers of the apparatus disposed in vertical alignment, indicating a condition of adjustment thereof.

In the accompanying drawings, the reference numeral 11 designates generally a supporting base which is a rectangular framework that may be made of right angle material covered by a sheet metal vertical wall enclosure. On the side horizontal angle bars of the frame 11 there are mounted two vertically extending guide rods 12 parallel to each other and each anchored in a supporting base 15 which may be integral with a bracket 16, Fig. 2.

The uppermost extremities of the two guide rods 12 are received in close fitting openings of a transverse beam 13 and the assembly is held rigid against sideward sway and vibration by means of guy braces or stay rods 14, each one of which consists of a threaded element secured to the base 11, another to the transverse beam 13, and an intermediate turn buckle 17 of the conventional right and left hand threaded design that may be drawn up to render the assembly rigid.

The transverse beam 13, in addition to its function of tying together the uppermost extremities of the guide rods 12, serves also as a hanging support through the link bolts 18 for a curtain bar 19 that is received within an endmost lap pocket sewn at one end of a strip of test fabric 21. The other end of the test fabric is similarly prepared and through the lower lap pocket there projects a similar curtain bar 22, the ends of which extend out beyond the width of the fabric 21, whereat they are provided with holes for receiving hanger hooks of a pair of spring scales 23. The lower ends of the scales 23 are hooked into eye bolt elements 24 carried by a transverse beam or angle bar (not shown) supported in the base 11. In this manner, and by regulating the tension through the medium of the wing nuts 26, a predetermined force may be applied to the test fabric 21 as indicated on the spring scales 23.

Before completing the above described suspension, the fabric is first threaded between a pair of cylindrical testing rollers 27 and 28, securely carried upon individual roller shafts 29 and 31, which in turn are journaled in the end bearing elements generally designated 32 and 33, Figs. 1, 3 and 4. The bearing elements 32 and 33 are similar and symmetrically opposite, each consisting of a principal bearing block 34, Fig. 4, and a pair of bearing caps 35 and 36, which are held down by the cap screws 37 and through which are threaded the adjustment screws 38 which will be discussed later.

Pivotedly associated with each block 32 and 33 is a vertical bearing extension 39 through which the guide rods 12 pass slidably. A pin 41 which may be integrally formed with and which extends sidewardly from each element 39 serves as a journal for the pivoted links 42 or 43, whose lower extremities are similarly pivoted in stud pins 44 of a pair of symmetrically opposite crank arms 45 and 46. The latter are secured at the ends of a power shaft 47 journaled in end bearings 48 and driven through a pulley wheel 49 and belt 51, by the driving pulley 52 which extends from a gear reduction box 53, Fig. 2, powered by an electric motor 54.

In order to be able to vary the stroke of the roller assembly each crank arm 45 and 46 is provided with a plurality of openings 55 into corresponding ones of which the stud pins 44 may be secured. The bearing block 34 is provided with an adjustment bolt 56 threaded through it and designed to impinge against the surface of a stud pin 57 integrally formed with the journal block 39 that slides on the guide rods 12 and extends through an appropriate opening in said bearing block 34. In this manner the position of block 34 may be secured so as to dispose the test rollers 27 and 28 one alongside the other, as viewed in Figs. 2 and 4, or one above the other, as viewed in Fig. 5.

It will be observed that the test fabric 21 in passing between the rollers 27 and 28 either as shown in Fig. 5 or as in Fig. 2 is subjected to a flexure reversal of corresponding variation in degree. This condition is produced because of the opposite manner in which the fabric wraps about the two rollers and of significance in this feature is the fact of rapid reversal of flexure which thereby produces the result of flexure test in a comparative short period of time.

Under conditions of test featured in Figs. 2 and 4, a greater amount of surface is brought into contact with the test fabric 21, than when the subject rollers are disposed in accordance with the illustration of Fig. 5. This affords a regulation for determining wear characteristics varying the contact surface area. In addition, by tightening the cap screws 38 either singly or together, the rollers 27, 28 may be made inert, affording a further means for regulating the test device so as to accentuate the subject under test to abrasion characteristics, whereas with the rollers running free, abrasion characteristics are subservient to wrinkle test characteristics.

It is contemplated that the test rollers 27 and 28, which are described as simple cylindrical elements, be covered in various manners by surface materials which have different abrasion characteristics. In this way the testing apparatus may be made to serve with increased effects on the abrasion characteristics. Likewise, these roller surfaces may be treated to reduce the friction characteristic if such should be the desired result. 75

During operation the motor 54, through its reduction gear box 53 imparts continuous reciprocal motion to the roller assembly guided on the rods 12 and in accordance with the length of stroke the test fabric 21 is subjected to flexing and/or abrasion until predetermined wear characteristics are observed.

While the present invention has been explained and described with reference to a more or less specific embodiment, it is to be understood, nevertheless, that a considerable range of variation and modification may be incorporated without departing from the essential spirit or scope thereof. Accordingly it is not intended to be limited by the details of the accompanying drawings, nor by the specific language in the foregoing description, except as indicated in the hereunto appended claims.

The invention claimed is:

1. In a wrinkling and abrasion fatigue testing apparatus, a pair of guide rods, means for suspending a strip of test fabric intermediate said rods under adjustable tension conditions, a pair of fatigue test rollers between which said fabric is threaded, said test rollers being journaled in slidable blocks guided upon said rods and including means for retarding said rollers against free rolling action in order to vary the abrasion imparting characteristics to said fabric strip.

2. In a fabric testing machine, means for suspending a strip of test fabric under tension, a pair of rollers between which said fabric is threaded, guide elements for directing reciprocatory movement of said rollers parallel to said strip, and guide roller journal elements comprising a member slidably supported on each of said guide elements, a journal box pivotally supported on said member and means carried by said box for controlling the freedom of movement of said testing rollers in order to vary the abrasion characteristics imparted to said strip.

3. In a fabric testing machine, means for suspending a strip of test fabric under tension, a pair of wrinkle and abrasion testing rollers between which said fabric is threaded, guide means for directing reciprocatory movement of said rollers parallel to said strip, guide roller journal elements comprising a bearing block, slidably supported on each of said guide means, and means for regulating the frictional drag of said testing rollers for thereby adjusting the abrasion characteristics imparted to said fabric strip under test.

4. In a fatigue testing apparatus, means for suspending a piece of material comprising a framework having oppositely presented bars and including a pair of spaced parallel tubular guide members, a set of fatigue testing rollers reciprocable on said tubular guide members and through which said material is threaded, and a mechanism for reciprocating said rollers on said guides for thereby effecting repeated abrasion and wrinkling contact with said material, said rollers being supported in opposite journal fixtures, including set screw means for each roller to be adjusted for effecting the locking to its journal of either or both of said rollers against rotation for thereby accentuating the abrasion component to which said material is subjected.
